DIMPING TOOL

Ralph A. Hawn and Irvin W. Lacher, Columbus,
Ohio, assignors to Curtiss-Wright Corporation,
a corporation of Delaware

Application June 18, 1943, Serial No. 491,416

1 Claim.

(Cl. 153—21)

This invention relates to dimpling tools, and more particularly to the construction of the same.

With the dimpling tools used heretofore, the construction has been such that the tool itself takes up considerable space so that the employment of the tool in narrow spaces is practically prohibited. Also the operable parts of the same are located externally of the tool and are free to be engaged by obstructions upon movement of the tool in and out of the difficult places. In other words, these operable parts are left unprotected and hence are readily put out of operation.

It is an object of the present invention to provide a dimpling tool which is of simple construction, cheap to manufacture, and adapted to be used in confined spaces.

It is another object of the invention to provide a dimpling tool which is so constructed that its operating parts are protected at all times and such that these parts can be readily disassembled so that they may be replaced quickly when desired.

According to the present invention the dimpling tool comprises an anvil member having a solid or thick portion and a depending skirt portion so connected with the thick portion as to provide a chamber within which is located a resilient operating or washer like rubber element adapted to bear against a collar portion on a peening member to normally maintain the peening member out of its finally extended position within a central bore of the thick portion of the anvil. This collar portion on the peening member not only serves to close off the chamber but serves as a means by which the peening member is locked to the anvil member. Within the chamber there is provided an annular recess into which is disposed a circumferentially expandable locking ring which, when seated in the recess, engages the collar portion of the peening member and prevents outward sliding movement thereof. When the peening member is maintained by the rubber element in a retracted position, a flared or countersink forming portion of the peening member, which serves to place the dimple in overlapped sheets of metal, is kept retracted so that the sheets may be positioned at first flat against the anvil member, this action having been effected by the engagement of the anvil member with a second anvil member forming a part of the dimpling arrangement. Once the metal sheets are rigidly retained, the peening member is actuated against the action of the rubber within the chamber of the first anvil member. The result is a dimple adapted to contain a rivet such that it will be flush with the

surface of the outer metal sheet, the action of the tool being such that portions around the opening are free of cracks which would have weakened the union of the rivet with the sheets.

For other objects and for a better understanding of the invention, reference may be had to the following detailed description taken in connection with the accompanying drawing, in which

Figure 1 is a view of a dimpling arrangement with the dimpling tool of the present invention shown in a cross section, the dimple having been formed within the metal sheets and the peening member still in its finally extended position.

Fig. 2 is a view similar to Fig. 1, illustrating a step in the process prior to the peening member having been located in its final position and with the metal sheets lying flat on the dimpling tool.

Referring now particularly to Figs. 1 and 2, there is shown a dimpling tool 10 having a depending shank 11 adapted to fit within a socket element 12 of a dimpling press or arrangement. Securement of the shank 11 with the socket 12 is made by a screw 13. Also serving as a part of the dimpling press is an upper anvil 14 secured to a socket 15 by a screw 16, the socket 15 being movable and moving with it is the anvil 14.

The dimpling tool 10 has a solid thick anvil portion 17 with an anvil face 18 thereon. This anvil face is hollowed so that as metal sheets 19 and 20 are depressed downwardly by the anvil 14 which has a slightly conical face 21 thereon, they will be slightly buckled just prior to the operation of a peening member 22 having a flared or countersink forming face 23 thereon. In the sheets 19 and 20 there are provided openings 24 adapted to register with a pilot formation 25 on the peening member 22. The sheets 19 and 20 are simply disposed over the pilot formation 25 and as the anvil 14, with its flared hole 15' registering with the pilot formation, is brought down onto the anvil face 18, the sheets will be slightly concaved or buckled, all this being done just prior to the engagement of the flared face 23 of the peening member with the portions of the sheets about the openings 24.

Once this step in the process has been completed, extension of the peening member 22 is effected to finally form the dimple in the sheets 19 and 20. On the thick anvil portion 17 is a depending skirt portion 26 serving to provide a chamber 27 within which there is located a washer like element 28 of resilient material, such as rubber, surrounding the peening member 22 and adapted to bear against a collar

formation 29 on the peening member. This washer element of resilient material is stiff enough to prevent relative movement of the peening member with respect to the anvil 17 while the sheets 19 and 20 are being brought flush between the anvil faces 18 and 21. After that time there is relative movement between the peening member and the anvil 17 and the peening member is forced upwardly through a central bore 30 to effect the dimpling operation. Portions 31 about the openings 24 in the sheets 19 and 20 are forced upwardly to make a clean countersink formation in the sheets, these portions being bent up at a sharp angle.

The collar formation 29 not only serves to close off the rubber element 28 within the chamber 27 but also serves as a means by which the peening member can be retained within the central bore 30 and coupled with the anvil 17. The outer periphery of this collar portion engages a circumferentially expansible locking spring 32 adapted to snap into an annular recess 33 in the lower end of the skirt portion 26 of the anvil 17.

It will be seen that the parts of this dimpling tool can be readily assembled and locked together by simply locating the locking spring 32 within the recess 33. At any time it is desired to disassemble the parts to replace either the rubber element 28 or the peening member 22, this locking spring 32 may be readily removed and parts freed of one another.

It should now be apparent that there has been provided a dimpling tool which is of simple construction, cheap to manufacture, and readily assembled or disassembled for replacement of its parts. It should also be apparent that its operating parts are concealed and free of any projections which might engage any obstructions adjacent to the location where the tool has been used. Also that the dimpling tool itself takes up very

little head space and that it is therefore adapted for use in confined places.

While various changes may be made in the detailed construction, it shall be understood that such changes shall be within the spirit and scope of the present invention as defined by the appended claim.

We claim as our invention:

10 In a tool for forming dimples in pre-punched sheet material, a unitary anvil having a working face and a bore opening centrally therethrough, the anvil bore being constituted by a reduced diameter section and an adjacent enlarged diameter section, said sections defining an internal wall therebetween, a peen constituted by an integrally formed body providing a first body portion slidably mounted in the reduced diameter bore section and a second and enlarged body portion slidably mounted in the enlarged diameter bore section, said first body portion being formed with a dimple forming end face which, upon relative sliding movement of said peen and anvil, is projectable or retractable relative to said anvil working face, and said second body portion defining with said internal wall and the wall of said enlarged diameter bore a chamber within said anvil, and a rubber-like element mounted on said first body portion and confined within said chamber for compression between said internal wall and the second body portion, said element being so dimensioned as to maintain the peen end face retracted with respect to said anvil working face when non-compressed but being deformable in a radial direction when compressed whereby said anvil and peen may slide relative to each other to project the peen end face relative to said anvil working face into the sheet material to form a dimple.
